(57) **CLAIM**

The ornamental design for an infrared thermal brush, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front angled view of an infrared thermal brush in accordance with the present disclosure;

FIG. 2 is a right perspective view thereof;

FIG. 3 is a front view thereof;

FIG. 4 is a rear view thereof;

FIG. 5 is a right side view thereof; and,

FIG. 6 is a left side view thereof.

The broken lines in the Figures show portions of the infrared thermal brush and environment that form no part of the claimed design.
